UNITED STATES PATENT OFFICE.

OTTO ARAM, OF ESSINGTON, PENNSYLVANIA, ASSIGNOR TO WESTINGHOUSE ELECTRIC AND MANUFACTURING COMPANY, A CORPORATION OF PENNSYLVANIA.

REFUSE GRINDER AND DISCHARGE MECHANISM FOR STOKERS.

1,405,814.

Specification of Letters Patent.

Patented Feb. 7, 1922.

Application filed June 9, 1920. Serial No. 387,612.

To all whom it may concern:

Be it known that I, OTTO ARAM, a citizen of the United States and a resident of Essington, in the county of Delaware and State 5 of Pennsylvania, have invented a new and useful Improvement in Refuse Grinder and Discharge Mechanism for Stokers, of which the following is a specification.

This invention relates to stoker mechanism 10 and particularly to the grate mechanism employed at the discharge end of the grate, and it has for an object to provide a dump-grate mechanism in the form of a clinker grinder, capable of gradually discharging the refuse 15 deposited thereon from the grate and of breaking up clinkers accumulating at the base of the grate.

With the usual form of swinging dump-grate mechanism, huge clinkers tend to accumulate 20 above the dump grate, thus obstructing the passage of refuse thereto and the discharge of refuse from the dump grate. Such clinkers are usually broken up by an iron bar inserted through a poke hole provided 25 in the furnace wall. The bar used for breaking the clinkers is usually heavy and cumbersome, and requires considerable effort to manipulate it, the operation frequently consuming much time and causing 30 damage to the rear wall and the grates.

A further object of this invention is to provide a dump grate which crushes the clinkers and passes them to the ash pit thereby preventing their accumulation upon 35 the dump grate.

More specifically the object is to provide a dump grate comprising a pair of grinding rolls and having simple operating mechanism for imparting rotary movement to the 40 rolls so that the rolls will be alternately rotated in opposite directions.

These and other objects are attained by means of stoker mechanism embodying the features herein described and illustrated in 45 the drawings accompanying and forming a part hereof, wherein:

Fig. 1 is a plan view of a dump grate and clinker grinder mechanism.

Fig. 2 is a side elevation, partially in section, of a dump grate mechanism showing its application to a furnace.

In Fig. 2, I show a dump grate mechanism applied to the discharge end of the grate 4 of a well known type of underfeed stoker, 55 which includes a moving grate 5 and a rear

furnace wall 6 spaced from the moving grate so as to provide a refuse discharge space or pit 7 into which the refuse is discharged from the moving grate.

The present dump grate and clinker 60 grinder mechanism is located in the pit 7 directly between the moving grate and the rear wall 6, and includes a pair of grinding rolls 8 and 9 disposed in parallel relation and provided with shafts 10 and 11 respectively, which are journaled in bearings 12 supported upon channels 13. Each roll comprises a heavy square central shaft 14 having bars or teeth 15 mounted on the four sides thereof in staggered relation, as indicated in Fig. 1. These bars perform the double service of supporting the fuel and refuse deposited thereon until complete combustion has occurred, and of crushing clinkers forming thereon or deposited thereupon from the upper grate. To facilitate the crushing action, the free ends of the bars are sharpened, as shown at 16, and the rolls are mounted so that when in operation, the bars of one roll are in a different angular 70 position from the bars of the other roll, and substantially in the relative position indicated in Fig. 2.

During the operation of the rolls, the angular relation of the bars of one roll with 75 respect to those of the other is approximately maintained, as indicated in Fig. 2, by means of a driving mechanism to be hereinafter described.

The rolls 8 and 9 are provided with ratchet 80 wheels 17 and 18 respectively, secured to their respective shafts and provided with ratchet teeth. The teeth 19 of the wheel 17 are inclined in a direction opposite to that in which the teeth of the wheel 18 are inclined and the wheels are, therefore, adapted to be rotated in opposite directions by means of pawls 21 and 22, respectively. Both of the pawls are pivoted to the upper end of an operating lever 23 which is pivoted for oscillation upon the shaft 10 carrying the roll 8. When the lower end of the lever 23 is moved to the left, the pawl 21 will engage the tooth 19 and rotate the wheel 17 in a clockwise direction, and at the same time 105 the pawl 22 will ratchet over the teeth 20 of the wheel 18 without imparting any movement thereto. Thus, during this movement of the lever, the roll 8 is rotated a determined distance, depending upon the degree 110

of movement of the lever 23 while the roll 9 remains stationary. When the lever 23 is returned to its original position by movement of the lever to the right, the pawl 22 will engage the teeth 20 of the wheel 18 and cause counter-clockwise rotation of the roll 9 an angular distance equal to that through which the roll 8 had been previously rotated, and while the roll 8 remains stationary. 10 During this movement of the lever 23, the pawl 21 ratchets over the teeth of the wheel 17 and therefore imparts no movement thereto.

It will be apparent from the foregoing that 15 the rolls are alternately rotated in opposite directions so that clinkers deposited thereon are shifted toward the space between the rolls and are crushed between the bars as the rolls rotate. It will also be seen that the 20 mechanism is simple and that the degree of rotary movement of the rolls may be varied by varying the degree of angular movement of the lever 23.

An operating rod 24 is pivotally attached 25 to the lower end of the lever 23, and extends to the front of the furnace, not shown, where it may be attached in any suitable manner to one of the reciprocating fuel feeding or agitating rams of the furnace, not shown, so that 30 the movement of the rolls is proportional to the movement of the said rams.

While I have described and illustrated but one embodiment of my invention, it will be apparent to those skilled in the art that various changes, modifications, additions and omissions may be made in the apparatus described and illustrated without departing from the spirit and scope of my invention, as set forth by the appended claims:

40 What I claim is:

1. Stoker mechanism comprising a grate, a pair of rotary crushing members disposed adjacent the discharge end of the grate and adapted to receive refuse from the grate, and 45 means for actuating the said members adapted to impart intermittent rotary movement alternately to each member.

2. Stoker mechanism comprising a grate, a pair of rotary crushing members disposed 50 adjacent the discharge end of the grate and adapted to receive refuse from the grate, and means for independently actuating each of the said members for alternately imparting rotary movement thereto.

55 3. Stoker mechanism comprising a grate, a pair of rotary crushing members disposed

adjacent the discharge end of the grate and adapted to receive refuse from the grate, and means for actuating the said members adapted to rotate the members in opposite directions and alternately impart rotary motion to each member. 60

4. A clinker grinder comprising a pair of rotary grinding members, a ratchet wheel on each member, an operating lever and a pawl for each ratchet wheel associated with the said lever in such manner as to actuate the said wheels alternately when the said lever is oscillated. 65

5. A clinker grinder comprising a pair of 70 rotary grinding members and means for rotating them in opposite directions comprising a ratchet wheel on each member, an operating lever and a pawl for each ratchet wheel carried by the said lever, the said pawls and 75 ratchet wheels being so arranged that movement of the lever in one direction causes one pawl to rotate the upper surface of one member toward the other member, and movement of the lever in the opposite direction 80 causes the other pawl to rotate the other member in the opposite direction.

6. A clinker grinder comprising a pair of 85 rotary grinding members and means for rotating them in opposite directions comprising a ratchet wheel mounted on each member, each having ratchet teeth inclined in opposite directions, a pivoted lever, a pawl for each ratchet wheel pivoted to the said lever and arranged with respect to their respective ratchet wheels that movement of the lever in one direction causes one pawl to operatively engage and rotate one of the ratchet wheels while the other pawl is caused to ratchet over the teeth of its respective 95 wheel, and movement of the lever in the opposite direction causes the formerly operative pawl to ratchet over the teeth of its respective wheel while the other pawl operatively engages and rotates the formerly inactive wheel. 100

7. A clinker grinder comprising a pair of rotary grinding members and means for intermittently and alternately actuating the said members, comprising a ratchet wheel on 105 each member, and oscillatory operating lever, and a pawl for each ratchet wheel actuated by the lever.

In testimony whereof, I have hereunto subscribed my name this fourth day of June, 110 1920.

OTTO ARAM.
